[57] CLAIM

The ornamental design for a combined wall mountable name plate holder and connector tab, as shown and described.

DESCRIPTION

FIG. 1 is a front elevational view of a combined wall mountable name plate holder and connector tab showing my new design, the rear being flat and plain;

FIG. 2 is a right side elevational view thereof;

FIG. 3 is a top view thereof;

FIG. 4 is a top, front, right perspective view thereof; and,

FIG. 5 is a bottom, front, right perspective view thereof.
